UNITED STATES PATENT OFFICE.

MATTHEW J. BOGERT, OF DEMAREST, NEW JERSEY.

DESIGN FOR A PILL-BOTTLE.

SPECIFICATION forming part of Design No. 28,731, dated May 31, 1898.

Application filed April 30, 1898. Serial No. 679,404. Term of patent 7 years.

To all whom it may concern:

Be it known that I, MATTHEW J. BOGERT, a citizen of the United States, residing at Demarest, in the county of Bergen and State of New Jersey, have invented a new and original Design for a Pill-Bottle, of which the following is a specification.

This invention relates to a new and original design for a pill-bottle; and it has for its object to provide a design of this character that shall be both useful and ornamental.

The leading features of the design reside in a cylindrical body provided with an exterior annularly-reduced neck portion, a pair of closely-arranged exterior annular beads at each end thereof, and a single annular bead surrounding the same at the juncture between the main portion of the body and its reduced portion. A minor feature of the design resides in the body having a stopper provided with a circular head, having its periphery formed by a pair of closely-arranged rounded annular beads.

In the drawings, Figure 1 is a perspective view of a bottle embodying the herein-described design. Fig. 2 is a side view thereof. Fig. 3 is a longitudinal sectional view.

Referring to the accompanying drawings,

the numeral 1 designates the cylindrical body of the bottle, which body is of the same interior diameter throughout and is provided with an exterior annularly-reduced neck portion 2, which curves into the main cylindrical portion of the body, and at the juncture between these two portions of the body is arranged a single annular rounded bead 3. At each of its opposite ends the bottle-body is provided with a pair of closely-arranged exterior annular rounded beads 4, and the stopper 5 is provided with a circular head having 40 its periphery formed by a pair of closely-arranged rounded annular beads 6, the said circular head of the stopper being of a less diameter than the adjacent end or mouth of the bottle-body. 45

What I claim is—

The design for a pill-bottle herein shown and described.

In testimony that I claim the foregoing as my own I have hereto affixed my signature in 50 the presence of two witnesses.

MATTHEW J. BOGERT.
